UNITED STATES PATENT OFFICE

121,136

DESIGN FOR A MIXER

Bernhart A. Benson, Chicago, Ill., assignor to Chicago Electric Manufacturing Company,
Chicago, Ill., a corporation of Illinois

Application November 14, 1939, Serial No. 88,284

Term of patent 7 years

To all whom it may concern:

Be it known that I, Bernhart A. Benson, a citizen of the United States, residing at Chicago, Cook County, Illinois, have invented a new, original, and ornamental Design for a Mixer, of which the following is a specification, reference being had to the accompanying drawing, forming a part thereof.

The dominant features of the design reside in the portions shown in full lines.

I claim:

The ornamental design for a mixer, substantially as shown and described.

BERNHART A. BENSON.
